CLAIM

The ornamental design for an aerosol delivery device as shown.

DESCRIPTION

FIG. 1 is a perspective view of the aerosol delivery device shown in an open, expanded position;

FIG. 2 is an alternative perspective view of the aerosol delivery device in an open, expanded position;

FIG. 3 is a left side view of the aerosol delivery device in an open, expanded position;

FIG. 4 is front view of the aerosol delivery device in an open, expanded position;

FIG. 5 is a right side view of the aerosol delivery device in an open, expanded position;

FIG. 70 is a rear view of the aerosol delivery device mouthpiece;

FIG. 71 is a top view of the aerosol delivery device mouthpiece; and,

FIG. 72 is a bottom view of the aerosol delivery device mouthpiece.
